C. W. STEEN

ADJUSTABLE MACHINE SUPPORT

Filed Oct. 31, 1921

Patented May 10, 1927.

1,628,620

UNITED STATES PATENT OFFICE.

CARL W. STEEN, OF NORWOOD, OHIO, ASSIGNOR TO ALLIS-CHALMERS MANUFACTURING COMPANY, OF MILWAUKEE, WISCONSIN, A CORPORATION OF DELAWARE.

ADJUSTABLE MACHINE SUPPORT.

Application filed October 31, 1921. Serial No. 511,719.

This invention relates in general to dynamo-electric and other machines, and it has particular relation to devices for facilitating the adjustment or positioning of a machine.

- 5 An ordinary design and construction of means for adjusting the position of a machine, as for belt-tightening purposes, etc., and for securing it in desired position includes the mounting of the machine on a support, such as one or more rails or slides secured in fixed position on a base or floor, and the provision of means for shifting the machines along the slides or rails and for holding the machine in adjusted position.
- 10 One form of this apparatus includes an integral abutment on the rail or other support, and an adjusting screw threaded through such abutment and bearing against the base or other portion of the machine, the adjusting screw being effective to shift the machine and to hold it in adjusted position. Another construction includes an abutment which is removable and adjustable to any one of several positions on the slide rail or other support.
- 15 The fact that the abutment is removable greatly facilitates the machining of the slide rails or other supports, for it readily permits the machining of a number of bases or supports in series, thus considerably reducing the cost of manufacture.

In accordance with the present invention, a slide rail or support is provided wherein the abutment for the adjusting screw is detachably mounted in and readily removable from desired operative position on the rail, the rail being preferably of the ordinary chambered type with an end closing wall for the chamber.

It is an object of this invention to provide an improved design and construction of supporting and adjusting devices for dynamo-electric and other machines, the same being relatively simple and efficient.

It is a further object of this invention to provide an improved design and construction of rail or base for supporting dynamo-electric or other machines and including a relatively fixed abutment capable of providing for the shifting of the machine to any desired operative position, the abutment being capable of being readily removed from and mounted in operative position.

It is a further object of this invention to provide an improved design and construction of supporting rail or base for a dynamo-

electric or other machine, which provides for the adjustable positioning of the machine on the support by means of an abutment mountable in one or several operative positions and capable of ready removal and insertion to operative position.

These and other objects and advantages are attained by this invention, various novel features of which will be apparent from the description and drawings, disclosing one embodiment of the invention, and will be more particularly pointed out in the claims.

In the accompanying drawings:

Fig. 1 is a front elevation of a motor, or other dynamo-electric machine, mounted upon supporting rails of a design and provided with devices embodying features of this invention.

Fig. 2 is an enlarged plan view of a portion of the rail shown in Fig. 1.

Fig. 3 is a broken vertical section along the line III—III of Fig. 2, with a machine held in adjusted position.

Fig. 4 is a vertical section along the line IV—IV of Fig. 2.

Fig. 5 is a plan view similar to Fig. 2, showing a modified form of the invention, providing for adjustment of the abutment.

Fig. 6 is a broken, vertical sectional view along the line VI—VI of Fig. 5.

Fig. 7 is a view similar to Fig. 5, showing a further modification.

Fig. 8 is an end elevation of the abutment of Fig. 7.

Fig. 9 is a broken vertical section along the line IX—IX of Fig. 7, with a machine held in adjusted position.

Figs. 10 and 11 are views similar to Figs. 3 and 4, respectively, showing a further modification, the sectional plane of Fig. 11 being substantially that of XI—XI of Fig. 10.

In accordance with the disclosure of Figs. 1 to 4 of the drawings, a motor or other dynamo-electric machine 10 is provided with supporting portions or feet 12 apertured, as indicated, for the reception of bolts for holding the motor in operative position. The motor is shown as being supported upon a pair of slide rails 14, each rail having at each end thereof a pair of oppositely extending feet or lugs 15 adjacent the lower edge thereof, these lugs being apertured to receive bolts for holding the rail in position on the floor or other support. The rail

is indicated as being recessed or chambered underneath and comprising substantially parallel side walls and a cross piece 16 constituting a top wall and connecting the sides adjacent the upper edges thereof and apertured, preferably centrally, adjacent the ends of the rail, as indicated at 17. As is an ordinary construction, the sides of the rail extend to the floor or other support and the space between the sides is closed at the ends by means of end walls, as indicated in Figs. 1 and 3. The upper side of the rail is provided throughout its length or at spaced points, as indicated, with upwardly projecting portions 18, one on each side of the central aperture 17 and both having machined upper surfaces designed to provide a seat and constituting slides upon which the base or feet of the machine may be shifted and is guided. The closed end of the rail is provided with an abutment shoulder 19 at the end of the elongated aperture 17 in the cross-piece of the rail.

The motor is held in position on the rails 14 by means of bolts 20 passing through the apertures in the feet 12, the bolts being provided with clamping and holding nuts 21 on the upper sides of the feet, the bolt heads 23 being disposed in the space between the side walls and beneath the cross-piece 16 of the rail. The bolts 20, one at each end of a rail, are held in spaced relation and in operative position against dropping, by means of apertured strips of sheet metal 24, the apertures in the strips being the same distance apart as the apertures in the supporting feet 12 of the motor. As indicated at 25, the ends of the strips 24 are turned up alongside the heads of the bolts. A securing device 26 in the form of an apertured piece of sheet metal through which the bolt 20 passes, is secured to the under side of the strip 24, as by spot welding thereto, and is provided with bent over extensions, as indicated at 27, at the under side of the bolt head, preventing the bolt from dropping out of position.

A removable abutment 31 is shown as comprising a body portion 32 having a threaded aperture extending therethrough longitudinally of the rail for the reception of an adjusting screw 33 designed to bear at its end against the foot 12. The under side of the body portion 32 is provided with a seat portion 34 designed to be received between the machined slides 18 of the rail and to rest upon the imperforate portion of the cross-piece 16, and preferably to have a relatively close sliding fit between the opposed walls of the slides 18 which will prevent substantial rotation of the abutment about a vertical axis when it is in operative position. A reduced shank portion 35 extends rearwardly at an angle of about 45 degrees from the lower rear part of the body

portion 32 and is provided at its lower end with a cross-head 36 of such width as to bear at each side on the lower face of cross-piece 16 of the rail, as indicated in Fig. 4.

The design of abutment is such that, when the body portion 32 rests upon the upper side of the rail, the upper face of the cross-head 36 may be in substantial engagement with the under side of the cross-piece 16. The lower side of the body portion 32 or the shank 35 is provided with a shoulder or projection 37 designed for bearing engagement with the abutment wall 19 on the rail when the removable abutment 31 is in operative position.

In placing the abutment 31 in operative position, it is turned on a vertical axis through an angle of 90 degrees from the position indicated in drawings. The cross-head 36 and the shank are of such size that with the abutment in the new position, the cross-head and the shank may be readily inserted through the aperture 17, after which operation the abutment may be turned back and the body portion dropped to operative position with the seat 34 resting on the cross-piece 16 between the slides 18. With the abutment in this position, the adjusting screw 33 may be threaded through the abutment and into engagement with the motor base or a foot thereof to shift the motor along the rail or to hold it in adjusted position, in which case the reaction of the adjusting screw against the abutment insures solid engagement of the shoulder 37 of the abutment against the abutment wall 19 of the rail and engagement of the seat 34 on the upper face of the cross-piece 16 and the cross-head 36 on the lower face of the cross-piece 16. Any tendency towards distortion in an angular direction about a vertical axis is resisted by the close engagement between the sides of the body portion 32 and the raised slides 18. As will be apparent, with the nuts 21 loose, the motor may be readily adjusted to any desired position, after which it may be held securely in such position by tightening the nuts 21.

Figs. 5 and 6 show a modification of the device illustrated in Figs. 1, 2, 3 and 4. This modification is such as provides for readily positioning the abutment 31 in any one of several operative positions. With this provision, it will be apparent that there may be almost any lower limit to the size of the motor or machine that may be satisfactorily held in operative position on a given support or set of rails. As indicated in Figs. 5 and 6, the body portion 32 of the abutment is provided with opposite downwardly extending lugs 45 in such position as to engage in opposed recesses or slots 46 in the side walls of the elongated aperture 17. It will be apparent that, with the lugs 45 in operative position in a pair of slots 46,

the walls of these slots act as bearing abutments for the front edges of the lugs or shoulders, taking up the reaction of the adjusting screw and thus serving to hold the abutment 31 in operative position.

In Figs. 7, 8 and 9, there is shown a further modification which provides for the adjustable positioning of the abutment 31. The body portion 32 of the abutment is provided with lateral extensions 51 which are designed to be received in slots or recesses 52 in the raised slides 18 of the rail. With the abutment in the position indicated, that is, with the lugs or extensions 51 in any pair of oppositely disposed recesses 52, the reaction of the adjusting screw 33 is such as to securely hold or lock the abutment in operative position.

In any of the forms of the invention disclosed, when the end of the adjusting screw is moved out of operative relation with the machine 10, the abutment may be shifted along the rail by first rotating it about a horizontal axis through the shank, probably adjacent the shoulder thereon which bears against a wall or abutment on the rail so as to lift the body portion 32 out of engagement with the upper side of the rail and the cross-head 36 out of engagement with the lower side of the rail.

In the modification shown in Figs. 10 and 11, the cross-piece of the rail is provided with one or a plurality of spaced apertures 17, as may be desired, leaving imperforate portions 56 in the form of spaced cross bars, the wall at the forward edge of each constituting a shoulder 19. Instead of a cross-head at the lower rear edge of the detachable abutment 31 extending beyond the sides of the aperture 17, this portion of the abutment, indicated at 57, is only of such width as to permit it to pass readily through the aperture 17 without the necessity of rotating the abutment about a vertical axis. The engagement of the end portion 57 with the under side of the cross bar 56 serves to hold the abutment in operative position. The abutment may be readily detached from any operative position by first rotating it to a limited extent about the end portion 57 and then lifting it in a substantially vertical direction.

It will be apparent, that, in accordance with the invention disclosed, there is provided an improved form of base or slide rail for supporting a motor or other machine in such a manner as to provide for shifting the motor on the base or slide rail, and wherein the rail or support may be of extremely simple form and readily cast or otherwise produced and machined, and further, wherein the abutment may be readily removed and placed in one or several operative positions as desired.

Another decided attribute of the present

invention is that existing patterns of the ordinary and usual type of rail having its abutment integral with the end portion of the rail, may be readily changed with practically no expense, so as to adapt it for casting a rail for use in accordance with the present invention. Again, rails of the old type now in existence may readily be transformed so as to accommodate for the use of the present invention merely by removing the integral and abutment present on the old type of rail.

It should be understood that the invention claimed is not limited to the exact details of the construction shown and described, for obvious modifications will occur to one skilled in the art.

It is claimed and desired to secure by Letters Patent:

1. In combination, a chambered support, the wall of said support at one side thereof being provided with a through aperture and having a shouldered portion about the aperture, and an abutment detachably mounted on said shouldered portion to operatively position the abutment, said abutment having a portion insertible through the aperture in the wall of said support, said insertible portion being adapted to lie within the chamber and to bear outwardly on the wall of said support when the abutment is in operative position thereon.

2. In combination, a support chambered at its lower side and provided with an elongated aperture through its upper wall, said support being closed at one end and having an abutment shoulder adjacent said end, and a unitary abutment having a body portion adapted to bear on the upper side of the support and engageable with said shoulder, and a portion insertible through the aperture in the support and engageable with the under side of a portion of said support.

3. In combination, a support comprising side walls and an apertured cross-piece connecting said side walls, said support being undercut beneath said cross-piece and closed at one end and having an abutment shoulder, and an abutment having a body portion bearing on the upper side of said cross-piece and a portion insertible through the aperture in said cross-piece and engageable with the under side thereof when said abutment is held in operative position on said support.

4. In combination, a support comprising side walls and an apertured cross-piece connecting the side walls, said support being chambered beneath the apertured portion of said cross-piece and having an abutment shoulder, and an abutment having a body portion bearing on the upper side of said support and a portion extending rearwardly at an angle from said body portion and through the aperture in said cross-

piece, said rearwardly extending portion having a cross-head at its lower end bearing against portions of said cross-piece at the sides of the aperture therein, and an element carried by and adjustable relative to the body portion of said abutment.

5. In combination, a support comprising side walls and an apertured cross-piece connecting said side walls and having a plurality of spaced abutment shoulders, and a detachable abutment having a body portion adapted to bear on the upper side of said cross-piece and interchangeably engageable with any one of said shoulders to variably 10 position the abutment on said support and having a portion insertible through, engageable with and adapted to bear upwardly on the adjacent side of said cross-piece when said abutment is in operative position on 15 said support.

6. In combination, a guide rail comprising side walls and an apertured cross-piece connecting said side walls at the upper side thereof, said rail being closed at one end 20 and having a plurality of spaced abutment shoulders, and a detachable abutment having an apertured body portion bearing on the upper side of said rail and interchangeably engageable with said shoulders to variably 25 position the abutment on said rail against thrust in the same direction and having a portion extending rearwardly at an angle from said body portion and insertible and removable through the aperture in said cross-piece and having an enlarged cross-head portion bearing upwardly 30 on the underneath side of said cross-piece.

7. In combination, a guide rail recessed 40 at its under side and having an aperture through its upper side communicating with the recess, said rail having raised slides at its upper side and an abutment shoulder, and a detachable abutment having a body portion 45 resting on the upper side of the rail and a portion with a guiding fit between said slides, said abutment having a portion engageable with the shoulder on said rail to position said abutment and a portion insertible and removable through the aperture in said rail and engageable with and bearing upwardly on the rail.

8. In combination, a guide rail comprising side walls and an apertured cross-piece 55 connecting said walls at the upper side thereof and closed at one end, said rail having a raised slide extending longitudinally of the rail at each side of the aperture therein and an abutment shoulder, and a detachable 60 unitary abutment having a body portion resting upon and with a guiding fit between said slides and engageable with said shoulder to position said abutment, said abutment having a portion extending rearwardly at an angle from said body portion 65

and through the aperture in said cross-piece and having an enlarged end portion insertible and removable through the aperture in said cross-piece and bearing upwardly against a portion of said cross-piece.

9. In combination, a guide rail comprising side walls and an apertured cross-piece connecting said side walls, said rail being undercut adjacent the aperture in said cross-piece and closed at the end thereof and having raised slides at the sides of the aperture and a plurality of spaced abutments on the apertured portion thereof, and a detachable abutment having an apertured body portion resting on said rail with a guiding fit between said slides, said abutment being interchangeably engageable with said shoulders to variably position the abutment against thrust in the same direction and having a portion extending rearwardly at 80 an angle from said body portion and extending through the aperture in said cross-piece, said extending portion having an enlarged end portion bearing upwardly on the underneath side of said cross-piece and 85 being removable through said aperture.

10. In combination, a guide rail comprising side walls and an apertured cross-piece connecting said walls at the upper side thereof and having a raised slide, said slide being provided with a plurality of spaced abutment shoulders, and a detachable unitary abutment having a body portion resting on the upper side of the rail and with a guiding fit between spaced portions of said slide, said abutment having an extension interchangeably engageable with the shoulders on said slide for variably positioning said abutment, and a portion extending rearwardly at an angle from said body portion and through the aperture in said cross-piece and bearing upwardly on a portion of said rail.

11. In combination, an undercut guide rail closed at its end and having an elongated aperture through its upper side and a plurality of spaced abutment shoulders at the upper side of said rail adjacent one end of said aperture, and an abutment having a portion interchangeably engageable with said shoulders to variably position said abutment against thrust in the same direction and a portion extending through said aperture and provided with an end portion insertible and removable through said aperture and adapted to bear upwardly against a portion of said rail when said abutment is in operative position on said rail.

12. In combination, an undercut support having an elongated aperture through its upper side and a plurality of pairs of spaced abutment shoulders at the upper side of said support along opposite sides of said aperture, and a unitary abutment carried by said support and having portions inter-

changeably engageable with said pairs of shoulders of the support and a portion extending through the aperture in the support and having an end portion bearing upwardly against a portion of the support.

13. In combination, an undercut support providing a chamber at its under side and apertured through the upper wall of the undercut portion, said support having a shouldered portion, an abutment adapted for detachable mounting on said support and co-operative with said shouldered portion, said abutment having a portion insertible through the aperture and adapted to bear on the under side of the upper wall of the chambered portion, and an element carried by and adjustable relative to said abutment, said abutment, when subjected to thrust exerted through said adjustable element, being adapted to forcibly bear against said shouldered portion, with one portion of the abutment bearing on the outer side of said support and a second portion of the abutment bearing on the under side of said support.

14. In combination, an undercut support adapted to support a structure mounted thereon, the undercut portion of said support being apertured through its upper wall and having a shouldered portion, an abutment co-operative with said shouldered portion and having a portion insertible through the aperture in the upper wall of said support and normally disposed in the chamber

of said support, and an element carried by and adjustable relative to said abutment and adapted to bear against said structure to operatively position the latter, said element being effective to maintain said abutment against said shouldered portion with the portion of the abutment disposed in the chamber bearing outwardly against the inner side of said support.

15. In combination, an undercut support adapted to support a structure mounted thereon, the undercut portion of said support being apertured through its upper wall and having a plurality of shouldered portions, an abutment detachably mounted on said support in co-operative relation with one of said shouldered portions and co-operative with the several shouldered portions, said abutment having a portion insertible through the aperture in the upper wall of said support and engageable with the inner side of said support, and an element carried by and adjustable relative to said support and adapted to bear against said structure to position the latter, the reactive thrust through said element being effective to maintain said abutment against the shouldered portion with which it is associated, with the insertible portion of the abutment bearing upwardly against the inner side of said support.

In testimony whereof, the signature of the inventor is affixed hereto.

CARL W. STEEN.
